PER

Issue, Nov. 5, 1872.

UNITED STATES PATENT OFFICE.

ISAAC J. VINCENT, OF PITTSTON, PENNSYLVANIA, ASSIGNOR TO THE UNION STOVE AND MANUFACTURING COMPANY, OF SAME PLACE.

DESIGN FOR A COOKING-STOVE.

Specification forming part of Design No. 6,241, dated November 5, 1872.

To all whom it may concern:

Be it known that I, I. J. VINCENT, of Pittston, in the county of Luzerne and State of Pennsylvania, have invented a new and original Design for a Stove called the "Star Cook," of which the following is a specification.

The accompanying photograph fully illustrates my new design.

This invention relates to a new design for cooking-stoves. It consists, first, in a new manner of ornamenting the oven-doors by four stars and projecting oval center ornaments, containing stars, as shown; also, in decorating the other side door by stars and oval center ornament; also, in ornamenting the circular registers of the front doors with rows of beads along the middle of each fixed

segment; and, finally, in the new oval ornament at the lower part of each front door, said oval having a star in the center.

Having thus described my invention, I claim as new and desire to secure by Letters Patent—

1. The design for the oven-door, as shown.
2. The design for the side door, as shown.
3. The design for the front registers, as shown.
4. The design for the lower ornaments of the front doors, as shown.

ISAAC J. VINCENT.
